(57) **CLAIM**

We claim the ornamental design for a freestanding enclosure, as shown and described.

DESCRIPTION

FIG. 1 is a front perspective view of a first embodiment of a freestanding enclosure in accordance with our new design; FIG. 2 is a top view thereof; FIG. 3 is a cross-sectional view taken along line 3-3 of FIG. 1;

FIG. 4 is front view thereof;

FIG. 5 is rear view thereof;

FIG. 6 is a left side view thereof, with the right side view being a mirror image;

FIG. 7 is a front perspective view of a second embodiment of our new design;

FIG. 8 is a top view thereof;

FIG. 9 is a cross-sectional view taken along line 9-9 of FIG. 7;

FIG. 10 is front view thereof;

FIG. 11 is rear view thereof; FIG. 12 is a left side view thereof, with the right side view being a mirror image;

FIG. 13 is a front perspective view of a third embodiment of our new design;

FIG. 14 is a top view thereof;

FIG. 15 is a cross-sectional view taken along line 15-15 of FIG. 13;

FIG. 16 is front view thereof;

FIG. 17 is rear view thereof;

FIG. 18 is a left side view thereof, with the right side view being a mirror image;

FIG. 19 is a front perspective view of a fourth embodiment of our new design;

FIG. 20 is a top view thereof;

FIG. 21 is a cross-sectional view taken along line 21-21 of FIG. 19;

FIG. 22 is front view thereof;

FIG. 23 is rear view thereof; and,

FIG. 24 is a left side view thereof, with the right side view being a mirror image.
